UNITED STATES PATENT OFFICE.

FRED C. WENDELL, DECEASED, BY THERESA S. WENDELL, ADMINISTRATRIX, OF NEW YORK, N. Y.

IRONING-MACHINE.

1,196,192.

Specification of Letters Patent. Patented Aug. 29, 1916.

Original application filed February 17, 1913, Serial No. 748,941. Divided and this application filed April 28, 1913. Serial No. 764,177.

To all whom it may concern:

Be it known that FRED C. WENDELL, deceased, late a citizen of the United States, invented certain new and useful Improvements in Ironing-Machines, of which the following is a specification.

This is a divisional application of the pending patent application filed February 17, 1913, Serial No. 748,941.

10 This invention relates to ironing machines wherein a heated drum combined with pressure rollers and an apron are used for feeding moist fabrics around the drum and pressing them around its periphery.

15 The principal object of the invention is to provide improved means for feeding the fabrics to the machine, whereby accidents to operators are prevented.

20 In this ironing machine, one of the drum journals constitutes the drive shaft, bevel gears are mounted on the drum journals, and a shaft driven by the driving gear drives the other gear and drum. Shafts rotated by said gears extend radially of said drums to

25 the apron drive-rolls to drive the aprons. Extensible shafts driven by the drum-gear extend radially of the drum to bevel-gears carried on the pressure rollers, whereby said rollers are driven. Steam cylinders are pro-

30 vided for the pressure rollers, and pistons therein are connected to the bearings of said rollers whereby uniform pressure is maintained upon said rollers and against the drum and intervening fabrics. An equalizing valve is interposed between the main steam line of the building and said cylinders, which reduces the steam pressure and maintains it uniform upon said pistons irrespective of the fluctuation of

35 steam pressure in the main line. Link-sets secured to the machine frame are connected to the bearings of the pressure rollers, and the sets being joined together by connecting links constitute complete trains of links at each side of the rollers. A steam cylinder fixed to the machine frame has its piston connected to said link trains. When the machine is not used, the steam is exhausted in the roller cylinders, and steam is ad-

40 mitted for an interval into the aforementioned cylinder, which sets said links to shift said pressure-rollers and to maintain them locked away from the ironing drum. To restore the pressure rollers to the drum,

steam is admitted into the opposite side of 55 said cylinder and the links thereby actuated to return to normal position. The pistons of the pressure-rollers are air-cushioned to retard the return movement of said rollers to the drum. A table is provided in front of 60 the feed apron of the machine, and a feed-roll is reciprocated partly over said table and partly over said apron, by arms and cranks connecting the roll to one of the pressure rollers. A pawl and ratchet prevent 65 rotation of said roll when moving over said table toward said apron. The operator places the fabric to be ironed upon the table, and while the feed roll moves away from the apron it rolls thereover. While return- 70 ing to the apron the roll grips the fabric and draws it over upon the apron, which feeds it to the machine. In this way the operator is not required to come in contact with the movable apron, whereby accidents 75 are prevented.

Other objects and advantages will hereinafter appear.

In the accompanying drawings, Figure 1 is a general side elevation of the ironing 80 machine. Fig. 2 is a fragmentary sectional view, taken on the line $x-x$ of Fig. 1, showing the driving mechanism of the pressure rollers. Fig. 3 is a general elevation of the opposite side of the machine, and shows the 85 mechanism for shifting the pressure-rollers and the safety feeding devices for the machine. Fig. 4 is an enlarged sectional view showing the piston and cylinder for the pressure rollers and the link mechanism 90 for shifting said rollers.

A hollow steel cylinder or ironing drum 1 is rotatably mounted on the machine frame 2, by its hollow journals 3 running in bearings 4 secured to said frame, and 95 a similarly oppositely revolving secondary drum 5 is rotatably mounted immediately below the drum 1, by its journals 6 running in bearings 7 of said frame. Said drums are disposed horizontally in the machine and parallelly to each other, and steam is admitted within the drums through the hollow journals 3 and 6, whereby the drum peripheries are heated and rendered suitable for ironing.

An endless apron 8 coöperating with the drum 1 is in rolling contact with its periphery at the lower side thereof and ex-

tends therefrom over a drive-roll 9, diagonally downwardly from said roll toward the drum 5, under an idle-roll 10, over a guide-roll 11, around idlers 12, 13, under a slack-roll 14, over an idler 15, and back to the drum. With the drum 5 co-operates an endless apron 16 which encircles it in rolling contact with its periphery, and extends therefrom over an idle-roll 17, from there over and around a drive-roll 18, thence over an idler 19, under a slack roll 20, around idlers 21, 22, over a guide-roll 23, under an idler 24, diagonally upward and around an idler 25, to an idler 26, and back to the drum. All of said rolls are provided with suitable bearings secured to the machine frame 2. The portion of the apron 16 from roll 25 to roll 26 is approximately parallel to the portion of the apron 8 from roll 9 to roll 10, and at the roll 9 the apron 16 is in rolling contact with the apron 8, so that said aprons run concomitantly toward the drum 5, due to the aprons running in opposite directions.

25 Pressure-rollers 28, preferably five in number, co-operate with the periphery of the drum 1 upon the upper side thereof for pressing fabrics thereagainst, and a feed-apron 29 provided at the feeding side 30 of the machine, slopes diagonally upward toward the first of said pressure-rollers 28^a, and conveys the fabric thereto. Said feed-apron passes around a board 31, the sharp edge 32 of which is disposed between the pressure roller 28^a and the periphery of the drum 1, and it extends around and is driven by a roll 33, mounted upon the machine-frame 2.

40 The journal 6 constitutes the drive-shaft of the machine and the drum 5 is thereby driven in a clockwise direction, as viewed in Fig. 1. A bevel gear 34 keyed on journal 6 meshes with a gear 35 fixed on a shaft 36 held in bearings 37 of brackets 37^a depending from the machine frame 2, and a gear 38 fixed to the opposite end of the shaft meshes with a bevel gear 39, keyed on journal 3, which is similar to gear 34, whereby the drum 1 is rotated in an opposite direction to the drum 5 and at the same speed. A shaft 40 mounted in bearings 41 is driven by a gear 42 thereon meshing with gear 39, and a gear 43 fixed on said shaft meshes with a gear 44 on the drive-roll 9 whereby the apron 8 is driven. A shaft 45 running in bearings 46 is driven by a gear 47 thereon meshing with gear 34, and a bevel gear 48 fixed to the shaft meshes with a gear 49 on the drive-roll 18, which 45 drives the apron 16. The feed-apron 29 is driven by its drive-roll 33 having a bevel gear 50 in mesh with a gear 51 of a shaft 52, running in bearings 53, which is rotated by a gear 54 thereon meshing with gear 34. 60 Gears 55, Figs. 1 and 2, in mesh with gear

39 are fixed on hollow shafts 56 extending radially of the drum 1 and held in bearings 57 formed on arms 58 depending from the frame 2; and shafts 59 fitting slidably within the shafts 56 and constituting extensible continuations of the shafts 56 are rotated thereby by means of keys and key ways at 60. The shafts 59 run in bearings 61 forming part of arms 62 carried upon the journals 63 of the pressure-rollers 28, and bevel 75 gears 64 fixed on shafts 59 mesh with gears 65 on the journals 63 whereby said rollers are rotated.

The moist fabric to be ironed is fed to the machine by the apron 29 and passes between the first pressure-roller 28^a and the periphery of the drum. It is then carried around the drum 1, and in contact with its hot surface, under the successive pressure-rollers 28 and between the endless apron 8 and the drum, during which course the fabric is thoroughly ironed on one side. From the drum 1 the fabric is carried over the roll 9 and between the concomitantly running portions 8^a and 16^b of the aprons 8 and 16 to the secondary drum 5. In passing over roll 9 and said concomitantly running portions of the aprons the fabric is reversed, so that its opposite side is presented to the hot surface of the drum 5, and being held pressingly thereto by the apron 16 running in rolling contact therewith the fabric is thoroughly ironed upon its opposite side while carried around this drum. Upon leaving the drum 5, the fabric is conveyed by the upwardly inclined portion 16^b of the apron 16 over the roll 18, where it is deposited in finished condition upon a delivery table 66 fixed to brackets 67 extending from the frame 2 opposite the feed side 30 of the machine. A doffer roller 68 held on arms 69 mounted on the roll 17 runs in rolling contact with the drum 5 and thereby prevents accidental climbing or sticking of the fabrics upon its periphery. A similar doffer roller 70 co-operates with the drum 1 above the roll 9 and serves a similar purpose therat.

The slack rolls 14 and 20 having bearings 71 slideable on guide-rods 72 fixed to frame 2 weigh down upon the aprons 8 and 16, whereby they are maintained taut while the machine is in operation and the required pressure of said aprons against the drums 1 and 5 is effected.

The journals 63 of the pressure-rollers 28 are mounted in bearings 73, Figs. 2 and 4, which are slideable in guiding ways 74 of guides 75, forming part of the frame 2, that extend radially from the center of drum 1. Steam cylinders 76 are secured to said guides, at each end of the pressure roller, by means of a flange 77 of the cylinder being bolted thereto, and pistons 78 co-operating with the cylinders have their piston-rods 79 secured to the bearings 73, by means of 120

heads 80 of said rods fitting in jaws 81 on said bearings. A bushing 82 threading into the top of the cylinder serves as a cylinder-head, and offers a convenient means of assembling during construction.

When the machine is in operation during ironing, steam is admitted into the cylinder 76 through the port 83 from the main steam line in the building, and a required pressure 10 is thus maintained above the piston 78 and transmitted to the bearings 73 of the rollers 28, whereby absolutely uniform pressure of said rollers against the drum and intervening fabrics is maintained at all times and 15 under all conditions, which is conducive to an even and fine grade of ironing work. In order to maintain a constantly uniform steam-pressure upon the pistons so that the resultant uniform pressure of the rollers 20 against the fabrics is of a non-varying force, the pistons are so proportioned that they require less pressure per square inch than that usually carried by the main steam line of the building, and an equalizing valve is 25 interposed between said line and pistons. Any fluctuation of pressure in the main line does not therefore affect the total pressure upon the pistons and rollers, and the force exerted by the rollers is consequently maintained uniform.

When the machine is not used, it is necessary to shift and maintain the rollers 28 out of contact with the drum 1 for the preservation of their felt peripheries. For this purpose a series of link-sets, Fig. 3, is provided on each side of said rollers, of which one link 84 is pivoted to the roller journal 63, and another link 85 pivoted to the frame 2 at 86 has its opposite end pivoted to link 84 at 87. Links 88 connect the series of link sets, and links 89 joined to the link-sets of roller 28^a, at each side of the machine, have their opposite ends 90 pivoted to cranks 91 fixed upon a rock-shaft 92, which is mounted 40 on frames 2 and extends the entire length of the machine. A steam cylinder 93 is fixed to frame 2 and a piston 94 therein has its piston-rod 95 connected to the crank 91, so that when steam is admitted for an interval 45 into the cylinder through the port 96, after the steam in cylinders 76 is exhausted, the entire train of link sets is drawn to the position shown in Fig. 4, whereby all of the rollers 28 are shifted away from the drum 1. The link-pivot at 87 is drawn past the straight line from the center of the roller to the pivot center at 86, and the link 85 abuts against a pin 97 fixed to frame 2, which causes the rollers to be locked in 50 shifted position, Fig. 4, and to be maintained away from the drum while the links are thus set. To restore the pressure-rollers 28 in pressed contact with the drum, steam is admitted for an interval into the opposite 55 end of the cylinder 93 through port 98 and

the links are thereby actuated and thrown to their normal position, Fig. 3, after which steam is admitted to the cylinders 76 to apply pressure upon the rollers. A small opening 99 is provided in cylinder 76 below the piston, so that the air is admitted into the cylinder thereat and operates to cushion the piston when the roller is returned to the drum, whereby its fall is retarded and too sudden a throw thereof prevented. If desired, a small opening 100 may be provided at the end 101 of the cylinder 93 which will cushion the piston 94 and thereby retard the return movement of the links to gently return all the rollers 28 to 30 the drum.

Each of the links 84 has an elongated hole or slot 84^a for the pivot joint at 87, which allows the roller 28 to rise, contrary to its pressure, when an immoderately thick fabric 35 passes thereunder, without affecting the remaining links of the train.

It will be evident that while the rollers are shifted, when actuated by the piston 94 or by fabrics passing thereunder, the gears 64 and 65 remain in mesh, due to the extensibility of the shafts connecting gears 64 and 55.

In front of the apron 29 is provided a table 102, secured to the frame 2, which partially extends over the upper feed surface of said apron and forms a continuation thereof. A feed-roll 103 is mounted on arms 104 pivoted to cranks 105 fixed to the journals 63 of pressure-roller 28^a, whereby 100 the cranks are revolved and said roll caused to reciprocate, forwardly away from the apron and backwardly, over a portion of said table and a portion of said apron. When traveling away from the apron said roll is rotated by contact with said apron and table, but upon the backward stroke of said roll over the table portion rotation thereof is prevented by a spring-pressed pawl 106 fixed to one of the arms 104 engaging a ratchet 107 fixed to the roll. As the roll continues over the apron-portion of its backward stroke it is caused to rotate in 105 rolling contact with said apron by the friction of the moving apron against its periphery.

The moist fabrics to be ironed are kept in a long receptacle 108 provided at the feed side of the machine below the table 102. When ironing, the operator spreads the fabric flat and places it upon the table 102, the surface of which is preferably polished, just before the commencement of the forward stroke of the feed-roll 103. Said roll then passes over the fabric, and being arrested against rotation upon its return stroke it grips the fabric and draws it over upon the apron 29 where it co-operates therewith to feed the fabric into the machine. The fabrics being placed successively upon 110

said table are thus taken up by the feed-roll and transferred to the apron, so that the operator's hands are never required to come in contact with the apron, and accidents, usually due to the hand getting caught by the moving apron between the drum and pressure-roller, are thereby prevented.

Variations may be resorted to within the scope of the invention, and portions of the improvements may be used without others.

Having thus described the invention, I claim:

1. In an ironing machine, the combination with a revoluble ironing drum, and a coöperating roller, of a continuously running feed apron traveling toward said drum and roller, a fixed table in front of said apron adaptable for placing thereupon a moist fabric to be ironed, a roll operated to travel toward and away from said drum and roller partially upon said table and partially over said apron in a motion of translation together with the running apron, and said roll being adapted and operated to engage the fabric and pull it from said fixed table and spread it upon said running apron and to hold the forward portion of the fabric against said apron while traveling in a motion of translation together with the fabric and apron for preventing operator's hands coming between said drum and roller.

2. In an ironing machine, the combination with a revoluble ironing drum, and a coöperating roller, of a continuously running feed-apron traveling toward said drum and roller, a fixed table in front of said apron adaptable for placing thereupon a moist fabric to be ironed, a roll adaptable to engage the fabric, means to operate said roll to travel toward and away from said drum and roller partially over said fixed table and partially over said running apron in a motion of translation together with the running apron, and said roll being adapted and operated to pull the moist fabric from said fixed table and spread it upon said running apron and to hold the forward portion of the fabric against said apron while traveling in a motion of translation together with the fabric and the apron for preventing operator's hands coming between said drum and roller, said roll pressing the fabric to said apron while traveling away from the apron.

3. In an ironing machine provided with an ironing drum, and a pressure roller, means for preventing accidents to operators including the combination of a continuously running feed-apron for the drum and roller, a fixed table in front of said running apron adaptable for placing a moist fabric thereon, a roll adaptable to engage the fabric, means to operate said roll to travel forwardly and backwardly partly over said

fixed table and partly over said running apron in a motion of translation together therewith, said roll being adapted and operated to pull the moist fabric from said fixed table and spread it upon said running apron and to hold the fabric against said apron while traveling in a motion of translation together with the fabric and the apron, and said roll pressing the fabric against said apron until the fabric enters between said drum and roller.

4. In an ironing machine, the combination with a revoluble drum, and a coöperating roller, of a continuously running feed apron traveling toward said drum and roller, a fixed table in front of said apron for placing thereupon a moist fabric to be ironed, a roll adaptable to engage the fabric, means to operate said roll to travel toward and away from said drum and roller partly over said fixed table and partly over said continuously running apron in a motion of translation together with the running apron, said roll being adapted and operated to pull the moist fabric from said fixed table and spread it upon said running apron and to hold the fabric against said apron while traveling in a motion of translation together with the fabric and the apron for preventing the operator's hands coming between said drum and roller, and said roll being rotated by said apron and pressing the fabric thereagainst while traveling away therefrom.

5. In an ironing machine, the combination with a revoluble ironing drum, and a coöperating roller, of a running feed-apron traveling toward said drum and roller, a fixed table in front of said apron adaptable for placing thereupon a moist fabric to be ironed, and an engaging device for the fabric actuated to travel forwardly and backwardly partly over said table and partly over said apron in a motion of translation together with the running apron to engage and spread the moist goods over said apron for preventing operator's hands coming between said drum and roller.

6. In an ironing machine, the combination with a revoluble drum, and a coöperating roller, of a running feed-apron traveling toward said drum and roller, a fixed table in front of said apron adaptable for placing thereupon moist goods to be ironed, and a roll actuated forwardly and backwardly to travel partly over said table and partly over said apron in a motion of translation together with the running apron to engage and spread the moist goods over the apron for preventing operator's hands coming between said drum and roller.

7. In an ironing machine, the combination with a revoluble drum, and a coöperating roller, of a running feed-apron traveling toward said drum and roller, a fixed

table in front of said apron adaptable for placing thereupon the goods to be ironed, and a roll actuated forwardly and backwardly to travel partly over said table and partly over said running apron in a motion of translation together with the running apron, said roll engaging the goods and spreading it over the apron on its forward stroke to prevent accidents to operators and 10 pressing out the goods against the apron on its backward stroke.

8. In an ironing machine, means for preventing accidents to operators including the combination of a continuously running 15 feed-apron for the machine, a fixed table in front of said apron adaptable for placing a moist fabric thereon, a roll extending over the entire width of said apron adaptable to engage the fabric, revoluble cranks, 20 arms joining said cranks with said roll, said

roll being actuated by said cranks to travel forwardly and backwardly partly over said fixed table and partly over said running apron in a motion of translation together therewith, and said roll being adapted and 25 operated to pull the moist fabric from said fixed table and spread it upon said running apron and to hold the forward portion of the fabric against said apron while traveling in a motion of translation together with 30 the fabric and the apron.

Signed at the city of New York, in the county of New York, and State of New York, this 26th day of April, A. D. 1913.
